UNITED STATES PATENT OFFICE

152,539

DESIGN FOR A POT AND PAN HANDLE

Andrew L. Henkel, Chicago, Ill.

Application January 15, 1947, Serial No. 136,159

Term of patent 7 years

(Cl. D44—26)

To all whom it may concern:

Be it known that I, Andrew L. Henkel, a citizen of the United States, residing at Chicago, Cook County, Illinois, have invented a new, original, and ornamental Design for a Pot and Pan Handle, of which the following is a specification, reference being had to the accompanying drawing, forming a part thereof.

Fig. 1 is a side elevation of a pot and pan handle showing my new design.

Fig. 2 is a top view showing the pot and pan handle of Fig. 1; and

Fig. 3 is a perspective view, from an elevated angle, showing the pot and pan handle of Fig. 1, and showing my new design.

I claim:

The ornamental design for a pot and pan handle, substantially as shown.

ANDREW L. HENKEL.
